BUTTERFLY PULL TOY

George W. Dunbar, Nashville, Tenn., assignor to Kusan,
Inc., Nashville, Tenn., a corporation of Kentucky

Filed Sept. 2, 1966, Ser. No. 3,722

Term of patent 14 years

(Cl. D34—15)

FIG. 1

FIG. 3.

FIG. 2

FIG. 4.

I claim:

The ornamental design for a butterfly pull toy, as shown.
